UNITED STATES PATENT OFFICE.

RALPH R. MCCLURE, OF SAN FRANCISCO, CALIFORNIA, ASSIGNOR TO JOHN H. ROSSETTER, OF SAN FRANCISCO, CALIFORNIA.

SIREN.

Application filed September 17, 1925. Serial No. 56,919.

This invention relates to sound producing devices and more particularly sirens, and has for its principal object to provide a hood or horn of the type designed for directing the sound wave emitted by a siren in a given direction preferably in a line parallel with the axis of rotation of the rotor. The invention consists preferably in means in the form of a tubular sound directing member 5 inwardly into which the air to the rotor passes and outwardly through which the sound emitting from the action of the rotor flows, and that embodiment illustrated consisting of a ported plate overlying a rotor 10 provided with radially open ended channels and including a hood extending forwardly from the plate and inwardly through which the air passes into the channels and outwardly through which the sound passes from the 15 plate ports.

In sirens in general use as at present designed, the air is admitted to the rotor through the center of its axis and the sound is emitted in a radial path, and is not directed 20 in any particular path, thus the efficiency of the siren for directional signalling is materially reduced.

This invention is particularly useful in 25 directing certain sound waves in a particular path where directional signalling is desired, thereby increasing the efficiency of the siren for this purpose and reducing the objections to the use of sirens due to the fact that the sound notes emitted therefrom discharge in 30 all directions and for certain uses render sirens obnoxious.

With the above mentioned and other objects in view, the invention consists in the 35 novel construction and combination of parts hereinafter described, illustrated in the accompanying drawings, and set forth in the claims hereto appended, it being understood that various changes in the form, proportion, size and minor details of construction within 40 the scope of the claims may be resorted to without departing from the spirit or sacrificing any of the advantages of the invention.

To more fully comprehend the invention, reference is directed to the accompanying 45 drawings, wherein—

Fig. 1 is a view in side elevation of the preferred embodiment of my invention.

Fig. 2 is a vertical longitudinal section.

Fig. 3 is a view in front elevation of a 55 siren rotor.

Fig. 4 is a view in longitudinal vertical section of an embodiment of the invention wherein the base plate forms a mounting for a parabolic sound deflector and wherein the bell mouthed core member falls short of extending flush with the edge of the deflector.

Fig. 5 is a view looking into the construction illustrated in Fig. 4, and

Fig. 6 is a vertical sectional view taken on line 6—6 of Fig. 3.

Referring to the drawings wherein like characters of reference designate corresponding parts throughout the several views, 1 indicates a standard carrying a motor casting 2 detachably secured thereto by a bracket 3. The casing is provided with an annular flange 4 to which is secured the rear face of a base plate 5. The plate is provided in its rear with a recess 6 and the wall of said plate is inclined outwardly toward the center of the plate as at 7, and is further provided in said inclined portion with an annular series of sound outlet ports 8. Within said series of ports 8 the plate is provided with an opening or port 9, and as illustrated 65

in Fig. 2 there extends outwardly from said port a tubular bell mouthed inwardly tapering air directing core 10, inwardly through which air passes to the rotor chambers hereinafter described. The core 10 is surrounded 75 in Fig. 1 by a parabolic sound deflecting or directing member 11 secured at its inner end to the base plate 5 at a point beyond the limits of the annular series of openings 8. The parabolic deflector directs the sound 80 waves passing through the ports 8 outwardly in a path surrounding the core 10.

Within the recess 6 is rotatably mounted a siren rotor 12 carried on the end of a motor shaft or other rotating means 13, and 85 the rotor is provided with a plurality of radial channels 14 opening at their outer ends in registry with the ports 8 and communicating at their inner ends with the air inlet 9. The rotation of the rotor 12 causes 90 air to pass inwardly through the core in the direction of the arrow through the channels 14 in the direction of the arrow, outwardly through ports 8 and outwardly through the space between the parabolic generator 11 and 95 the outer surface of the core 10 as indicated 100

by the arrow, thus it will be observed that the sound waves are directed by the hood in a direction substantially parallel with the axis of rotation of the rotor, and are precluded from emission radially of the rotor casing as is the common practice.

In Fig. 4, the tapering core 10 has been materially reduced in length as it terminates at a point well within the deflector 11. In 10 this construction as well as in the preferred embodiment, the parabolic sound deflector is employed, and while this form is preferable, showing the greatest efficiency in sound direction, it is to be understood that its shape 15 may be departed from if desired.

Having thus described my invention what I claim as new and desire to protect by Letters Patent of the United States is:—

1. In combination with the rotor of a 20 siren provided with open ended channels, said channels disposed radially of the rotor with their outer ends opening toward one face of the rotor near its periphery and the inner ends opening toward the same face of 25 the rotor near its center, a ported plate overlying the face of the rotor and provided centrally with a port common to the inner ends of said rotor channels and with an annular series of ports with which the outer ends of 30 said channels register on the movement of the rotor, and a hood extending forwardly from said plate near its periphery and inwardly through which air passes into said central port and outwardly through which 35 the sound passes from said annular series of ports.

2. A sound directing and air inlet hood for sirens comprising a plate provided centrally with a port and further provided with 40 an annular series of ports surrounding said central port, and a pair of concentrically ar-

ranged tubular directing members carried by and extending forwardly from the face of said plate.

3. In combination with the rotor of a 45 siren, a sound directing and air inlet hood therefor, comprising a plate positioned in advance of the rotor and provided with a centrally located air inlet opening and further provided with a plurality of sound outlet openings disposed circumferentially of 50 said inlet opening, and a tubular directing member carried by and extending outwardly from the face of the plate and said member being of a diameter to enclose said series of 55 sound outlet openings.

4. A sound directing and air inlet hood for sirens comprising an open ended tubular member, its inner open end being circumferentially flanged outwardly and said flange being provided with a plurality of sound outlet openings disposed circumferentially of the tubular member, and a second 60 directing member extending outwardly from the periphery of the flange with said first 65 tubular member disposed centrally thereof, the inner member falling short of projecting beyond the end of the outer tubular member.

5. A sound directing and air inlet hood 70 for sirens including a base provided with an air inlet opening and a plurality of sound outlet openings and a tubular sound directing hood extending from one face of the plate, said sound directing hood mouth and 75 said air inlet opening being disposed in relative concentric relation with the end of said air inlet opening falling short of projecting beyond the end of said hood mouth.

In testimony whereof I have signed my 80 name to this specification.

RALPH R. McClure.
